UNITED STATES PATENT OFFICE

PETER EDWARD CALLEN, OF TORONTO, ONTARIO, CANADA

HEAD NUMBER FOR HORSES

Application filed January 5, 1929. Serial No. 330,478.

The principal object of the invention is to avoid confusion in determining the position of horses in a race, by enabling the judges to see the number while retaining the focus of their vision on the horse's head.

5 A further object is to obviate the necessity of placing the number placards upon the rider which are both unsightly and inconvenient.

10 A still further object is to provide a number which can be very quickly placed securely in position or quickly removed.

The principal feature of the invention consists in providing a number placard adapted 15 to be detachably secured to the head harness of a horse.

In the drawings, Figure 1 is a perspective view showing the arrangement of the number on the head harness of a horse.

20 Figure 2 is an enlarged perspective view of the front of the number placard.

Figure 3 is an enlarged perspective view of the back of the number placard.

In the racing of horses it has been customary to fasten large and unsightly number placards on the saddle of the horse and on the arm or back of the rider or driver.

30 The saddle number is frequently obscured in a race by the position of the horse in relation to other horses or riders. So also the number carried by the rider is frequently in a position not readily discernible by the judges and it frequently happens in judging a close race that the judges have to await the 35 return of the horses past the "judges' stand" before they can determine the number of a horse picked for position, as the number was not discernible in the flash past the tape.

It is necessary in the judging of the finish 40 of a race to watch the horses' heads closely and after the tape has been passed the judge requires to shift his focus of vision from the horse's head back to the saddle or to the rider to find the number.

45 The present invention has been devised to overcome these objectionable features by the placing of a clearly legible number placard upon the head harness in such a way that the number will be directly in the line of vision 50 of the judges and will be seen concurrently

with the horses' heads in the finish of the race, consequently there will be no hesitation on the part of the judges or no waiting on the part of the judges or spectators in knowing 55 the winner of the race.

The device consists of a substantially rectangular placard 1 which may be formed of a fabricoid or oil cloth or any suitable medium stiff material that will hold its shape. The face of this placard is preferably a material of a dull white finish and on this is secured 60 a number 2 preferably of black faced material.

Upon the back of the placard 1 and preferably adjacent to the upper right hand corner is secured a clip member 3 which is formed of a strip of suitable spring metal having a hook-shaped upper end 4. The lower inside portion 5 is preferably formed with a pair of pointed lugs 6 which are inserted through the back member of the placard 1 and cleated down.

65 The hook end 4 is adapted to hook over the brow strap 7 of the horse's bridle.

A short strap 8 is stitched or otherwise secured to the back of the placard adjacent to the lower corner below the member 3 and the free end of this strap is provided with a fastener member 9 preferably a dome head to engage the fastener member 10 secured intermediate of the width of the placard member.

70 The strap 8 is adapted to pass under the side bridle strap 11 and the end is held by the fastener 10.

75 The number when thus placed upon the bridle is held securely at the side of the horse's head in such a position that the number is very prominently displayed and no effort is required on the part of the judges to determine the number separately from determining the position of the particular horse.

80 The material from which number placards are made is sufficiently pliable to not be objectionable for use on the horse as it will not cut or scratch in any way. It may be slipped into position with a very rapid movement and secured firmly in place so that it will not become displaced in any way.

The material used and the arrangement of the fastening members are such that the placard will not be objectionable to the horse. It will not flap in the wind but fits snugly against the side of the head back of the eye and is of course in such a position as to be readily discernible from all angles and therefore easily and positively distinguished.

What I claim as my invention is:

- 10 1. A head number for horses, comprising a placard formed of a stiff fabric sheet presenting a light coloured ground on the outward side and a number in a dark coloured material secured to the face of said sheet, and means secured to the back of said placard for detachably securing same to the head harness.
- 15 2. The combination with the head harness, of a placard having a number on one side detachably secured to said head harness with the number outermost.
- 20 3. The combination with the head harness, of a placard numbered on one side, and means secured to the opposite side of said placard detachably engaging said head harness.
- 25 4. The combination with the bridle, of a placard numbered on one side, means arranged at the top of the placard for detachably engaging the brow band of said bridle, and means arranged at the bottom of the placard for detachably engaging the side strap of said bridle.
- 30 5. The combination with the bridle, of a placard numbered on one side, a hook member secured on the opposite side of said placard for hooking over the brow band of said bridle, and means on the back of said placard for engaging the bridle and holding the bottom end of the placard.
- 35 6. The combination with the bridle, of a placard presenting a numbered surface on one side thereof, means at the top of the placard on the opposite or reverse side thereof for detachably securing same to the head band of said bridle, and a strap secured at one end to one edge of the placard at the bottom thereof below said former means and adapted to pass around the bridle side strap, and means for fastening the end of said strap.
